UNITED STATES PATENT OFFICE.

FRANCIS HEATH, OF HUDDERSFIELD, ENGLAND, ASSIGNOR TO THE HEATH WRAPPER COMPANY, OF LITTLEMOOR, MIRFIELD, ENGLAND.

WRAPPING MACHINE.

1,423,324.

Specification of Letters Patent. Patented July 18, 1922.

Application filed November 28, 1920. Serial No. 426,435.

(GRANTED UNDER THE PROVISIONS OF THE ACT OF MARCH 3, 1921, 41 STAT. L. 1313.)

To all whom it may concern:—

Be it known that I, FRANCIS HEATH, a subject of King George V of Great Britain, residing at Huddersfield, in the county of 5 York, England, have invented a new and useful Improvement in Wrapping Machines (for which I have filed an application for patent in England on March 1, 1919, No. 139,610), of which the following is a specification.

This invention has reference to the wrapping of caramels, sweetmeats, bars of soap or the like in paper or foil, and comprises improved automatic or self-acting means for 15 feeding and cutting the paper to the proper length, feeding a caramel block or bar forward thereto and to be embraced within the folded length of paper and then carried forward into the path of gripping jaws which 20 are timed to seize upon the ends of paper projecting beyond each edge of the caramel and to twist same, or alternatively instead of jaws for twisting the projecting ends of paper, fingers may be provided for folding 25 the paper on three sides at each end, the last or fourth side being folded over by suitable guides as the wrapped caramel block or bar is moved forward to the point of discharge from the machine, each operation being ap- 30 propriately timed so that the several motions operate synchronously to effect the complete wrapping of each caramel block or bar as it is fed through the machine. In the accompanying drawings, to which reference 35 will hereinafter be made:—

Fig. 1 is a side elevation of a machine embodying my invention;

Figs. 2, 3 and 4 are enlarged side elevations partly in section of the blank feeding 40 device, and illustrate respectively different stages of the feeding operation, as will be described later;

Fig. 5 is a front view of the paper feeding and cutting devices;

Fig. 6 is a section taken on line A, B 45 Fig. 5;

Fig. 7 is a plan view of the machine; and Fig. 7^a is a plan view of a few parts at the upper part of Fig. 7, certain of which are 50 not shown in Fig. 7 for lack of space.

Figs. 8, 9 and 10 are cross sectional views

of the conveyer device, and illustrate respectively different stages of the conveying operations, as will be described later;

Figs. 11, 12 and 13 are elevations of the 5 gripping jaws, and some of their operative parts and illustrate respectively different stages of the operation of gripping and twisting up the ends of paper on a blank;

Fig. 14 is a front view of the folding 60 mechanism;

Figs. 15, 16 and 17 are also front views of the folding mechanism and illustrate different stages of the folding operation;

Fig. 18 is a side elevation of the folding 65 mechanism;

Fig. 19 is an end view of a part of the folding mechanism, looking in the direction of the arrow D, Fig. 18.

The mechanism forming my new or improved machine may be said to comprise four groups, namely (1) mechanism for feeding in the caramels, sweetmeats or other articles which for the sake of description I shall refer to as the blanks; (2) paper 70 feeding and cutting mechanism; (3) what I term conveying mechanism which conveys the blanks along with the individual or severed portions of paper in which they are to be wrapped, into position to be operated on by the twisting or folding mechanism, and (4) mechanism for twisting up the ends of the paper projecting beyond each edge of the blank or alternatively, mechanism for folding the projecting ends of paper. 75 80 85

I will first describe the blank feeding mechanism. This comprises a suitable feed guide-way, as for instance a trough 1 in or along the bottom of which runs an endless belt or travelling apron 2 passing around 90 suitably supported rollers 3 and 4. The belt or apron 2 may be driven in any convenient manner, as for instance by means of a bevel 5 on the axis of the roller 4, the said bevel 5 meshing with a bevel 6, on the axis 7 of 95 which is a pulley 8 driven by band 9 from a pulley 10 fast on the main driving shaft 11 of the machine. An intermittent drive may if preferred or found more convenient, be given to the feed belt 2 instead of the continuous drive imparted by the mechanism just described. 100

The feed guide trough 1 is disposed at right angles, see Fig. 7, to a main feed guide 12 in which is located, and adapted to be slid endwise, a pusher or plunger 13 actuated 5 through a lever 17 and connection 18 from a cam or eccentric motion, not shown, on the driving shaft 11 of the machine. Mounted above the pusher 13, and capable of independent longitudinal movement, is a second 10 slide 16 actuated by a lever 14 and connection 15 from a second cam or eccentric motion, also not shown, on the driving shaft 11.

The pusher or plunger 13 carries, at its front end, a wedge shaped or inclined members 19, 19 located one on each side of the main guide-way, and between such members 19, 19 is located a pivotally mounted yielding or flexible bent finger 20. The action 20 of the parts 19 and 20 will be described later.

The upper or main slide 16 has on its upper side a shoulder 21 formed at an appropriate point in its length, with which shoulder is adapted to engage, at the proper 25 time, a finger 22 pivoted at one end at 23 to the main guide framing. A suitable spring 24 acting on the upper side of the finger 22 tends to force it down into position to engage with the shoulder 21, and a connection 30 25 from a lever 26 pivoted intermediate its ends and acted upon by a pin 14^a on the lever 17 serves to raise the free end of the finger 22 above the path of the shoulder 21 as shown in Figs. 2 and 3.

35 The construction of the paper feeding and cutting mechanism will now be described. A vertically movable rod or bar 27 has a toothed portion 28 with which engage toothed pinions 29, 29. These pinions 40 through pivoted pawls 30, 30 engaging ratchets 31, 31 on respective shafts 32, 32 are adapted to drive said shafts in one direction of movement of the bar 27 that is to say when the said bar is moved in a downward 45 direction. During upward movement of the bar, the pawls 30, 30 ride idly over the teeth of the ratchets 31, 31 and leave the shafts 32, 32 at rest, as will be understood. The shafts 32, 32 carry feed rollers 50 33, 33 which are grooved, see Figs. 5 and 6, to permit of vertical movement between them of a series of vertical guide-wires 34 carried by a crosshead or frame 35 attached to the bar 27.

55 The wrapping paper strip 36, unwound from a roller the like supported in any suitable manner and position on or in proximity to the machine, is led over a bar 37 and passed or threaded between the guide wires 60 34 so as to be loosely held in extended condition and is then passed through the nip of the feed rollers 33, 33. Suitable guide channels 38, 38 receive and guide the edges of the paper strip.

65 Located in suitable position beneath the

guide rollers are respective fixed and movable cutter blades 39 and 40. The movable blade 40 is actuated at the required time by a lever 41 operated by a connection, not shown, from a swinging frame 42 moved 70 by a cam 43 on the driving shaft 11.

Intermittent vertical movements are imparted to the bar 27 by lever 44, see Fig. 1, 75 acted upon by cam 45 on the driving shaft which cam acts to draw down the said bar, whilst a cam 46 acting upon the lever 44 through lever 47 and link 48 gives a quick upward movement to the bar.

Downward movement of the bar 27 causes the feed rollers 33, 33 to pull on the paper strip and feed down a predetermined length between the fixed and movable cutting members 39 and 40 which are at this time open. The cross-head 35 carrying the guide wires 34 being attached to the bar 27, the said 80 wires move down in the grooves in the feed rollers and deliver the paper between the cutting members in properly extended condition.

On the bar 27 being moved upwardly, the 90 guide wires are retracted or carried back to their original raised position but, through the idle movement of the pawls 30 over the ratchets 31, the feed rollers remain at rest so that the length of paper carried down by the 95 previous rotation of the feed rollers is left in position between the fixed and movable cutting members ready to be severed at the proper time. Any liability to backward rotation of the feed rolls through pull on the 100 paper is guarded against by ratchet discs 49, 49 on the shafts 32, 32 the teeth of which discs are engaged by holding pawls 50, 50.

The conveying mechanism comprises a shaft 51 adapted to be intermittently rotated to the extent of half a revolution at the required time by means of bevels 52, 53 shaft 54, pegs 55 on said shaft 54, and star wheel device 55^a on the driving shaft 11.

The shaft 51 carries a frame 56, on rods 110 57, 57 in which are fast the inner ends of pairs of arms 58, 58. Also mounted on the rods 57, 57 but loosely, are the inner ends of pairs of levers 59, 59. The outer ends of the pairs of arms, 58, 58 are connected by rods 115 or rollers 60, 60 and the outer ends of the pairs of levers 59, 59 are connected by rods or rollers 61, 61.

Working through an opening 62 in an enlargement on the shaft 51 is a pin or rod 63 or preferably two openings and rods spaced at suitable intervals apart are employed and each end of the rod or rods 63 carries a cross bar 64 or 65.

Encircling the rods 57, 60 and 61 is an 125 endless belt or sheet 66 which is suitably clamped to the respective cross bars 64 and 65. The length of the rod or rods 63 is or are such that when one crossbar is presented to the exterior of the device, that is to say 130

between one pair of cross rods 60 and 61, as shown for instance on the left in Fig. 8, the other crossbar 65 occupies a position towards the centre of the device or near the 5 shaft 51, thus causing the endless belt or sheet 66 to form, along with the other pair of cross rods 60 and 61 a jaw or pocket, as shown on the right of Fig. 8. The pivoted levers 59 are pressed upon near their free 10 ends by suitable springs 67, 67 (Fig. 7) which cause each pair of cross rods 60 and 61, in combination with the endless sheet 66, to form a spring jaw. If desired the arms 58 could also be pivoted and spring 15 pressed inwardly in the same manner as the levers 59. Mounted on cross rods 68, 69 above and below the shaft 51 are respective partly-circular metal plates 70 and 71 which are adapted as the device is rotated through 20 its half revolution at each operation to form closures for the inlet end of a rear or delivery guideway 72 located at the opposite side of the conveyer device in alignment with the main guideway 12.

25 Suitable fixed stops 73 and 74 are provided to engage the projecting ends of the cross-bars 64 and 65 and serve to accurately position the conveyer device, after each actuation or half rotation, in correct alignment opposite the feed and delivery guideways.

A crossbar 75, supported and movable vertically in brackets 76 and 77 (Figs. 2, 3, 4 and 5) occupies a position immediately in 35 front of the conveyer device. As the pusher 13 comes forward the bar 75 is moved up out of the way by the wedge-shaped members 19 of the pusher 13, or by the finger 20 when used, which engages with its lower 40 edge, as shown in Fig. 3, and on said pusher withdrawing, the bar drops down on to the slide 16 and forms a scraper for the end of same. The bar 75 also serves to prevent the blank from being withdrawn from the conveyer by the rearward movement of the slide 45 16 in the possible event of the blank adhering to the end of the said slide.

It will be obvious that the conveyor device might if desired be arranged to revolve 50 about a vertical axis instead of about a horizontal axis as above shown and described.

Coming now to the fourth group of mechanism namely that for twisting up the ends of paper projecting beyond the edges of a 55 blank after the paper has been placed in position around same in the manner which will be described later, or alternatively for folding down the projecting ends of paper over the blank instead of twisting the said 60 ends, I will first describe the twisting mechanism.

This comprises pairs of gripping jaws 78, 78 and 79, 79 each pair of which is pivotally carried by a shaft 80 capable of being 65 slid laterally in bearings 81, 82. Slidable

on each shaft 80 is a jaw positioner 83 having spring members 84, 84 adapted to bear on the edges of the jaw levers and cross bars or loops 85 of any approved construction adapted when the jaw positioners are in a 70 certain position, as for instance, that shown at Fig. 11, to bear against the tails 78^a and 79^a of the jaw levers and hold the jaws open. Between collars 83^a on each jaw positioner is mounted a boss 86 having slotted projections 87, in the slots of which work fingers 88 of levers 89 pivoted at 90 and having their other arms slotted at 91 to receive fingers 92 projecting from a shaft 93.

Movement of the levers 89 on their pivots 80 in one direction causes the jaw positioners to move inwards from the position shown in Fig. 11 to that shown in Fig. 12, the effect of which movement is to cause the jaws to be closed by reason of the spring members 85 84, 84 bearing on the jaw levers and rocking them on their pivots.

Further movement of the levers 89 on their pivots now results in the shafts 80 being bodily slid endwise in their bearings in 90 an inward direction, that is to say from the position shown at Fig. 12 to that shown at Fig. 13. This inward movement of the shafts is provided to compensate for the shortening of the projecting ends of paper 95 which between the position shown at Fig. 12 and that of Fig. 13, have been twisted up by the rotation of the shafts 80 and consequently of the gripping jaws, such rotation being effected by means of pulleys 94, 100 94 bands 95, 95, and pulleys 96, 96 on a shaft 97 to which rotation is imparted by means of a friction disc 98 acted upon at the proper time by a friction surface 99 on a wheel 100 on the driving shaft 11. One band 95 is 105 open and the other crossed, so as to cause the two pairs of jaws to be rotated in opposite directions.

The rocking of the levers 89 on their pivots to effect the inward movement of the 110 jaw positioners to close the jaws, and the subsequent inward movement of the shafts 80 to carry the jaws nearer to the blank to compensate for the shortening of the twisted ends of paper is effected as follows:— 115 The shaft 93 carrying the actuating fingers 92 for the levers 89, has fast upon it an arm or finger 101 which is adapted to be engaged at the proper time by a pin 102 on a disc 103 on the driving shaft. This pin 102 effects the closing of the jaws, and the subsequent inward movement of the shafts 80 is effected by a cam 104 which engages and gradually raises the arm or finger 101 still further beyond the point to which it has 120 been swung by the pin 102, thus gradually rocking the shaft 93 and, through the connections, bringing about the effect desired. Outward movement of the shafts 80, and the restoration of the jaw positioners to normal 130

position to again open the gripping jaws, is effected by a pin 104^a on the disc 103, which engages an arm or finger 105 on the shaft 93 and rocks it in the reverse direction 5 to that in which it was moved by the action of the pin 102 and cam 104 on the arm or finger 101.

In order to retain the shafts 80 in their outward positions until the commencement 10 of the twisting operation calls for their inward movement each shaft is provided with a finger 106 which is adapted to be engaged by a finger 107 fast on a shaft 108, the said fingers 107 normally occupying the position 15 shown in Fig. 7, that is to say, being on the inner sides of the fingers 106. They are held in this position by the engagement with an arm 109 on the shaft 108 of a cam 110 on the wheel 100 or of a pin 111 on said wheel. A 20 spring, not shown, acts to rock the shaft 108 in a direction to carry the fingers 107 away from the shafts 80 when neither the cam 110 or the pin 111 is presented beneath the arm 109. The cam 110 serves to move the 25 fingers 107 into operative position whilst the shafts are in their outward positions. Then it leaves the arm 109 and the fingers 107 are moved away by the spring mentioned, to permit the shafts to move inwardly, the angle to which the said fingers 30 107 are moved being such that the fingers 106 can rotate clear of them during the twisting operation. When the rotation of the shafts 80 ceases, on the twisting being completed, the pin 111 acts on the arm 109 and 35 causes the fingers 107 to be moved into operative position for a short time. Since the fingers 106 are at this time opposite to the fingers 107 owing to the inward movement 40 of the shafts 80, the movement into operative position of the fingers 107 serves to bring the shafts 80 to rest with the gripping jaws in vertical alignment ready for the next closing operation. This having been done, 45 the fingers 107 are permitted to move out to inoperative position to permit the shafts 80 to move outwardly to normal position, when the cam 110 again acts to restore the fingers 107 to the position shown in Fig. 7. 50 The delivery guide 72 is carried by a saddle 72^b pivoted at 72^b to the machine frame, so that the said delivery guide can if necessary pivot in an upward direction to ensure correct alignment of the blank with respect 55 to the axis of the gripping or twisting jaws.

The mechanism for folding the ends of 60 paper projecting beyond the edges of the blank, and which may be employed instead of the gripping jaws and twisting mechanism just described, is constructed as follows:— Mounted above the inlet end of the rear or delivery guideway 72 are a pair of fingers 113, 113 pivoted together at 114 and capable of being raised and lowered vertically by fingers 115, 115 attached to or form-

ing part of a horizontally disposed lever 116, pivoted at 117. The opposite end of the said lever 116 is connected by link 118 to an arm 119 on a shaft 120, which takes the place of the shaft 97 in the twisting mechanism. 70

The upper ends of the fingers 113 are provided with projections 121, 121 which, as the said fingers are lowered, are adapted to engage a fixed surface 122, mounted on the top of the upper portion of the guideway 72, as 75 shown in Fig. 14, and cause the said fingers to be rocked on their pivot, with the result that their lower ends move inwardly. During the lowering of the fingers their lower ends come into contact with the upper portions of the paper projecting beyond the ends of the blank, so that as the fingers are rocked as above stated, the said upper projecting portions of paper are engaged and folded inwardly against the ends of the blank, as 80 85 will be understood by reference to Figs. 14 and 15.

Mounted on a shaft 123 supported in suitable bearings beneath the machine and driven by suitable means from the driving 90 shaft 11 is an eccentric 124 the strap of which carries two fingers 126, 126 which project up through a slot 127 in a suitably disposed fixed member 128. These fingers 126 are located one on either side of the delivery 95 guide and are adapted under the action of the eccentric 124 and of the slotted member 128, to engage and fold back the front sides of the projecting ends of paper. A pair of wipers 129, 129 mounted on a spindle 130 100 and located one on either side of the guideway 72 in rear of the fingers 113 and 126 are adapted on rocking of their spindle to come forward and fold down the rear sides of the projecting portions of paper. Movement is imparted to the spindle 130 through arm 131, connection 132, and arm 133 from a rock shaft 134. This shaft has fast upon it an arm 135 adapted to be acted upon by a projection 136 on a disc 137 on the driving 105 shaft 11 to rock the said shaft in one direction and an arm 138 adapted to be engaged by a projection 139 on the disc 137 to rock the shaft in the opposite direction. 110

The action of the fingers 113 and 126, and 115 of the wipers 129 results in the folded ends of paper being left projecting downwardly as will be understood from Figs. 16 and 17. In order to complete the folding operation by bending these projecting folded ends up 120 against the ends of the blank, the said folded ends, as the blank is moved rearwardly along the delivery guide-way by fresh blanks being presented to the folding mechanism, are caused to pass between horizontal 125 plates 140, 140 one pair being provided at each side of the guideway. The front edges 141 of the lower plates are cam shaped and raise the folded flaps or ends from the vertical position in which they are left by the 130

wipers 129 into a horizontal position. As the blank passes clear of the rear ends of the plates 140 the horizontally extending folded flaps or ends are engaged by pivoted members such as 142 one at each side of the guideway and are folded up against the ends of the blank. Motion is imparted to the members 142 through links such as 143, from a lever 144 pivoted at 145 to a fixed 10 bracket 146 and acted upon by a roller 147 carried by an arm 148 on the rock shaft 120. The shaft 120 may be actuated by the engagement with an arm 149 thereon of a suitable cam on the driving shaft 11 or in any 15 other convenient manner.

The paper is now completely folded about the blank but in order to give a finished appearance to the folded up ends of paper, at the ends of the blank, I provide a pair of 20 spring plates 150, 150 located one on each side of the rear end of the delivery guide. These plates 150 are adapted to be swung upwardly on their pivots by a connection 151 from a lever 152 acted upon by a suitable cam on the driving shaft 11, and in 25 their upward movement they rub against the folded up ends and by such upward rubbing pressure exerted on the blanks give a nice square finish to the fold.

30 The action of the machine is as follows:—

The unwrapped blanks are fed by hand or by any suitable mechanical device into the trough 1 and are carried forward by the travelling apron 2 toward the main guideway 12.

35 The pusher 13 is caused by its actuating cam to move toward the conveying device, and as the said pusher with its inclined or wedge shaped members 19, 19 arrives at the 40 paper (a predetermined length of which has been fed down past the cutters during the previous cycle of operations of the machine) the latter is severed by the cutters.

45 As the pusher 13 with its inclined or wedge shaped members 19, 19 arrives at the paper, the predetermined length of the latter is severed by the cutters and is carried by the members 19, 19 against the cross bar 64 or 65 of the conveyor device, whichever 50 may happen at the moment to be presented at the inlet side of the device. The engagement of the members 19, 19 with the cross-bar concerned moves it from the position shown on the left of Fig. 8, to that shown 55 on the left in Fig. 9, this movement causing the endless belt or sheet 66 with its cooperating pair of cross rods 60, 61 to form a pocket for the reception of the blank. The upper surfaces of the members 19, 19 being 60 inclined, the rod 61 carried by the spring pressed levers 59 will if necessary be raised to provide a jaw or pocket of sufficient depth to receive the blank.

Meantime a blank has passed from the 65 feed trough into the main guideway 12 and

is engaged by the end of the slide 16 which by the action of its operating cam is caused to move endwise and to carry the blank toward the conveying device. In so doing it forces the blank beneath the yielding finger 20 causing the free end of the latter to raise the cross rod 61 still further to assure the blank getting fully and freely into the jaw or pocket in the conveying device and into the folded paper positioned therein by 70 the pusher 13. 75

The position of the feed mechanism is now that shown at Fig. 3.

The forward movement of the pusher 13, by reason of the pin 14^a on its operating lever 17 having moved clear of the lever 26 has allowed the forward end of the latter to drop and thus cause the free end of the finger 22 to drop down into a position to engage the shoulder 21 on the slide 16. 80 85

The blank having been fed into the conveying device along with its portion of wrapping paper the pusher 13 commences to move backwards. The upper slide 16, however, by reason of the engagement of the finger 22 with the shoulder 21 is held for a short time in a slightly withdrawn position, as shown at Fig. 4, to guard against accidental withdrawal of the blank as the pusher commences to move back. On the arrival 95 of the pusher 13 at its rearward position the finger 22 is, by the connections described, raised clear of the shoulder 21 and the slide 16 completes its movement back to its original position. The position of the 100 blank in the conveyor at this stage is shown at Fig. 9. The members 22, 23, 24 and 25 are provided to prevent the withdrawal of a blank which may stick to the end of the plunger 13 which is moved backwardly in 105 advance of the backward movement of the slide 16.

During the backward movement of the slides 13 and 16 the paper feed mechanism 110 operates to carry down the end of the paper strip a predetermined distance below the cutting members where it is left by the guide wires which are carried back by the upward movement of the bar 27 to their raised position clear of the cutters. 115

The movement of the cross bar 64 or 65 by the pusher 13 as the latter came forward carried the projecting ends of the crossbars clear of the fixed positioning stops 73 and 74 leaving the conveying device free to be 120 rotated. As soon, therefore, as the pusher 13 and slide 16 have withdrawn, a half revolution is given to the conveying device by its driving mechanism in the direction of the arrow C Fig. 9, thus carrying the blank 125 which has been placed therein from its position opposite the feed guideway 12 into a position opposite the delivery guideway 72 as shown at Fig. 10.

This half revolution of the conveyor pre- 130

sents the other crossbar opposite the feed guideway and the feeding operation is repeated. The placing of the second blank in the conveyor results in the first blank being expelled therefrom as will be understood from an examination of Figs. 8 to 10 and such first blank moves out into the delivery guideway 72.

The length of the severed piece of paper 10 and its position as it is carried into the conveyor by the pusher 13, is such that as the blank is placed into the conveyor it is wrapped on three sides by the act of insertion whilst a sufficient portion of paper is 15 left projecting at the upper side of the pocket to cover the fourth side. During the half revolution of the conveyor just described, the projecting portion of paper referred to is wiped or folded down by an inclined plate 112 so that when the blank passes from the conveyor into the delivery guideway it is wrapped on all four sides and the portions of paper projecting beyond its ends are ready to be twisted or to 25 be folded as the case may be.

I will assume first that they are to be twisted.

On the arrival of the blank in the delivery guideway the gripping jaws 78, 79 are 30 closed in the manner already described, the shaft 80 carrying them being meantime held from endwise movement. As soon as the jaws have closed upon the portions of the wrapping paper projecting beyond the 35 ends of the blank the friction surface 99 comes into action and, through the friction disc 98 and driving connections from the shaft 97, commences to revolve the shafts 80 and the gripping jaws to twist up the 40 gripped projecting ends of the wrapping paper. Simultaneously with the commencement of the twisting operation the cam 104 comes into action and as before described causes the shafts 80, 80 to be slid inwardly 45 to gradually carry the jaws closer to the blank as the projecting ends of paper shorten. On completion of the twisting operation the gripping jaws are opened, and the shafts 80, 80 moved back to their original outward positions ready for the next gripping and twisting operation.

During the time the twisting operation just described has been proceeding the paper feeding and blank feeding mechanisms have 55 again commenced to operate, and as soon as the gripping jaws have opened a third blank is placed in the conveyor. This causes the second blank to move from the conveyor into the delivery feed guide and 60 the now completely wrapped and twisted first blank to be forced along the delivery guideway towards the outlet end thereof.

The cycle of operations described is repeated and continues so long as a supply of 65 blanks is present in the feed trough 1, and

when the supply ceases, the last presented blank will be operated on and wrapped and the machine completely emptied.

If, instead of being fitted with the twisting mechanism described, the machine is arranged to fold down the portions of paper projecting beyond the ends of the blank, then upon movement of a wrapped blank from the conveyor into the delivery guideway the fingers 113 are operated to fold in 75 the upper projecting portions of paper and the fingers 126 and wipers 129 operate successively to fold the front and rear side portions. The blank is then moved by the pressure of incoming blanks along the delivery 80 guide the folded ends being raised from the vertical to the horizontal by cam shaped or curved front ends of the lower plates 140. On the blank passing clear of the plates 140, the members 142 bend up the folded ends 85 against the ends of the blank and finally the folded and bent up ends are rubbed square and neat by the plates 150.

If desired a second and narrower strip of paper may be fed to the machine along with 90 the ordinary wrapping paper to provide a band or open-ended covering, the meeting edges of said band when folded being secured by an adherent substance in known manner.

It will be obvious that the details of construction of my machine may be altered and varied in many ways without departing from or exceeding the scope of my invention.

Having thus described my invention, what 100 I claim as new and desire to secure by Letters Patent is:—

1. In a wrapping machine, a conveyer for the blanks, a guide arranged crosswise of the conveyer, a pusher slidable in the said guide 105 under the conveyer and having a positioning device at its front end, a slide arranged above the conveyer and adapted to push a blank off it into engagement with the said positioning device, and means for sliding the 110 pusher and the slide independently of each other.

2. In a wrapping machine, a conveyer for the blanks, a guide arranged crosswise of the conveyer, a pusher slidable in the said guide 115 under the conveyer and having wedge-shaped positioning members at its front end, a pivoted positioning finger for holding a blank between the wedge-shaped members, a slide arranged above the said conveyer and adapted to push a blank off it into engagement with the said finger and wedge-shaped members, and means for sliding the pusher and the slide independently of each other.

3. In a wrapping machine, a horizontally 125 arranged pusher having a positioning device for a blank at its front end, a slide arranged over the pusher and adapted to place a blank into engagement with the positioning device, means for sliding the pusher and 130

the slide independently of each other, and a vertically movable scraper for the front end portion of the slide, said scraper being raised and lowered by the said positioning device.

- 5 4. In a wrapping machine, a horizontally arranged pusher having a positioning device for a blank at its front end, a slide arranged over the pusher and adapted to place a blank into engagement with the positioning device,
10 means for sliding the pusher and the slide independently of each other, a stop which engages positively with the said slide and prevents its premature backward movement, and means for disengaging the said stop
15 from the slide periodically.

18 from the first periphery.

5. In a wrapping machine, a pair of grooved feed rollers for the wrapping material, vertically slideable wire guides for the wrapping material which slide in the grooves 20 of the said rollers, means for revolving the pair of rollers intermittently to feed the wrapping material from the wire guides, means for raising the wire guides while the feed rollers are stationary, cutters operating 25 to sever the wrapping material when the wire guides are raised, and a reciprocating pusher arranged below the cutters.

6. In a wrapping machine, a slidable pusher; a wrapping and conveying device adapted to receive a blank and a sheet of wrapping material from the pusher, said device comprising a revoluble frame, an endless apron supported by the frame, cross-bars secured to the end portions of the apron and operatively connected together, and means for revolving the frame intermittently to place the said crossbars alternately in the path of the pusher, the crossbar for the time being on the inlet side of the device being adapted to form a pocket in the apron in which the blank is positioned by the pusher, and the other crossbar being adapted to eject the previously inserted blank.

7. In a wrapping machine, a slidable pusher; a wrapping and conveying device adapted to receive a blank and a sheet of wrapping material from the pusher, said device comprising a revoluble frame, an endless apron supported by the frame, cross-bars secured to the end portions of the apron and operatively connected together, means for revolving the frame intermittently to place the said crossbars alternately in the path of the pusher, the crossbar for the time being on the inlet side of the device being adapted to form a pocket in the apron in which the blank is positioned by the pusher; and a stationary plate arranged tangentially of the wrapping and conveying device and operating to wrap the wrapping material over the fourth side of the blank while the said device is being partially revolved.

8. In a wrapping machine, a slidable pusher; a wrapping and conveying device adapted to receive a blank and a sheet of

wrapping material simultaneously from the pusher, said device comprising a revoluble frame, arms supported by the said frame, certain of the said arms being movable pivotally, an endless apron supported in the frame by the said arms, crossbars secured to the end portions of the apron and operatively connected together, and means for revolving the frame intermittently to place the said crossbars alternately in the path of the pusher, the crossbar and arms for the time being on the inlet side of the device being adapted to form a laterally yielding pocket in the apron in which the blank is positioned by the pusher. 70 75 80

9. In a wrapping machine, a ⁸⁰ slideable pusher; a wrapping and conveying device adapted to receive a blank and a sheet of wrapping material simultaneously from the pusher, said device comprising a shaft having an opening crosswise of its axis, a frame secured on the said shaft, crossbars arranged on opposite sides of the said shaft, a coupling-rod secured to the crossbars and slideable in the opening in the said shaft, an ⁸⁵ endless apron having its end portions secured to the said crossbars and having its intermediate portions slidably supported by the said frame and adapted to form a receiving pocket for the blank and the wrapping material on the inlet side of the device when the crossbars and coupling-rod are slid forwardly by the pusher, and means for revolving the said shaft intermittently to place the crossbars alternately in the path of the ⁹⁰ ⁹⁵ ¹⁰⁰ pusher.

10. In a wrapping machine, a slidable pusher; a wrapping and conveying device adapted to receive a blank and a sheet of wrapping material from the pusher, said device comprising a revoluble frame and an endless apron supported thereby and forming a pocket in which the blank is positioned by the pusher, means for partially revolving the said device to convey the partially wrapped blank from one side of it to the other, means for wrapping the fourth side of the blank while the said device is being partially revolved, a delivery guideway into which a wrapped blank is forced by the forward movement of the pusher, and means for closing the wrapping material over the ends of the blank while same is supported by the said guideway. 105 110 115

11. In a wrapping machine, means for 120
folding the ends of a portion of strip wrap-
per about a blank, comprising a delivery
guide into which the wrapped blank is fed,
a pivoted lever above said guide carrying
a pair of pivotally connected fingers adapted 125
to have a downward and inward movement
to engage and fold inwardly the upper pro-
jecting portions of the wrapper, a pair of
fingers located one on each side of the de-
livery guide and operated by an eccentric 130

- to fold back the front sides of the projecting ends of the wrapper, a pair of wipers one on each side of the delivery guide adapted to be swung about their pivot centre
- 5 to fold back the rear sides of the projecting ends of the wrapper, the means to raise the folded flaps or ends of the wrapper into a horizontal position as the blank moves along the guideway, and the pair of pivoted members one on each side of the guideway acting to raise and fold up the said flaps against the ends of the blank, all substantially as shewn and described.
- 10 12. The combination with mechanism ac-

cording to claim 11, of a pair of pivoted plates 150 one on each side of the delivery guide, such plates having inclined spring faces adapted as the said plates are swung upwardly on their pivot to gradually put pressure on the ends of the folded blank, 20 substantially as and for the purpose shewn and set forth.

In testimony whereof I affix my signature in the presence of two witnesses.

FRANCIS HEATH.
